(57) **CLAIM**

The ornamental design for a paper roll dispenser, as shown and described.

DESCRIPTION

FIG. 1 is a view of a backside of a paper roll dispenser showing our new design.

FIG. 2 is a top view of the paper roll dispenser showing our new design.

FIG. 3 is a front view of the paper roll dispenser showing our new design.

FIG. 4 is a bottom view of the paper roll dispenser showing our new design.

FIG. 5 is a left side view of the paper roll dispenser showing our new design.

FIG. 6 is a right side view of the paper roll dispenser showing our new design; and,

FIG. 7 is a perspective view showing the bottom and back top views of the paper roll dispenser showing our new design. The broken-line disclosure represents unclaimed portions of the article in which the claimed design is embodied.

1 Claim, 4 Drawing Sheets
